[57] ABSTRACT

A system for controlling the choke valve of an internal combustion engine comprises a diaphragm box having therein a pair of diaphragms spaced apart from each other to define therebetween a liquid chamber which is filled with a liquid whose viscosity varies in accordance with temperature change. A partition wall having an orifice defined therethrough bisects the liquid chamber and negative pressure from the intake manifold of the engine acts upon one of the diaphragms to actuate the other of said diaphragms which has attached thereto an operating rod connected to the choke valve of the engine. The responsiveness of the control system varies with temperature as a result of the changing viscosity levels of the liquid contained within the liquid chamber.

FIG. 3

CHOKE CONTROL SYSTEM FOR INTERNAL COMBUSTION ENGINES

BACKGROUND OF THE INVENTION

The present invention relates generally to choke valve control systems for internal combustion engines and more particularly to a system whereby the choke valve may be forcibly moved to its fully opened position in response to negative pressure from the intake manifold of the engine.

Normally, during the phase of engine operation when an engine is not as yet sufficiently warmed up, fuel vaporization occurs at a lower rate and as a result combustion of the air-fuel mixture does not occur readily. It is therefore necessary under such operating conditions to supply a richer fuel mixture to the engine, and for this purpose there is ordinarily utilized a choke valve which is adapted to throttle air flow at the inlet of the carburetor while drawing fuel in greater quantities. Such choke valve is usually fully opened when the engine has achieved a sufficiently warm condition.

Automatic choke valves which are arranged to be gradually opened by automatic action of a bimetallic member, which may be heated either by engine exhaust gas or by an electric heater, are commonly known. More recently, however, improvements have been developed in connection with the engine warming mechanism which reduce the utility of the choke valve. However, harmful components, such as CO and HC, occurring in the exhaust gases released from the engine will be present in greater amounts when the engine is not warmed up as compared to a condition when the engine is warmed up. Accordingly, it is desirable to quickly open the choke valve at a point when the engine has achieved, to a certain degree, its warm condition.

To this end, there has previously been proposed a choke valve opening device which utilizes a diaphragm mechanism operated by the vacuum from the intake manifold. Generally, when ambient temperature is low, a longer warming time is necessary than that required at normal temperatures. Accordingly, under such low temperature conditions, the choke valve must be opened slowly. However, in prior art choke valve opening systems, the choke valve will be always opened at the same speed and thus there occurs a likelihood that the operating condition of the engine at cold start will be impaired.

The present invention is directed toward overcoming such problems by providing an improved choke valve control system which lowers the choke valve opening speed in order to prolong the warming time of the engine at cold start and thereby enhance operating performance.

SUMMARY OF THE INVENTION

Briefly, the present invention may be described as a choke valve control system for an internal combustion engine which includes an intake manifold and a choke valve, said control system comprising, in combination, a diaphragm box, a pair of diaphragms located within said box and spaced apart from each other to define a liquid chamber therebetween, a liquid contained within said chamber adapted to undergo viscosity change in accordance with changes in temperature, a partition wall within said box bisecting said liquid chamber, orifice means defined through said partition wall, a choke

valve operating rod interconnected between one of said diaphragms and said choke valve and movable through an operating stroke between positions into and out of driving engagement with said choke valve, a diaphragm chamber defined within said box by the other of said diaphragms on a side thereof opposite said liquid chamber, negative pressure conduit means connected between said intake manifold and said diaphragm chamber, and spring means biasing both said diaphragms toward a direction tending to place said operating rod out of driving engagement with said choke valve. Introduction of the negative pressure in the diaphragm chamber is communicated through the liquid chamber to drive both the diaphragms in a direction tending to bring the operating rod into driving engagement with the choke valve. When this occurs, the negative pressure of the intake manifold is utilized to open the choke valve. However, due to changes in viscosity in the liquid contained within the liquid chamber, the responsiveness of the control system will be altered by changing ambient temperature conditions, and accordingly a lesser degree of choke valve opening will occur during starting of an engine under low temperature conditions.

The various features of novelty which characterize the invention are pointed out with particularity in the claims annexed to and forming a part of this disclosure. For a better understanding of the invention, its operating advantages and specific objects attained by its use, reference should be had to the accompanying drawings and descriptive matter in which there is illustrated and described a preferred embodiment of the invention.

DESCRIPTION OF THE DRAWING

In the drawing:

FIG. 1 is a schematic block diagram of a choke valve control system in accordance with the present invention; and

FIGS. 2 and 3 are illustrative views showing in greater detail a check valve of the system depicted in FIG. 1.

DETAILED DESCRIPTION OF THE PREFERRED EMBODIMENT

Referring now to the drawing there is shown in FIG. 1 a carburetor 1, an intake manifold pipe 2, an exhaust manifold 3 and a throttle valve 4 located within the body of the carburetor 1. A choke valve 5 is arranged to be controlled by a bimetallic member (not shown) which may be heated either by the exhaust gases of the engine or by an electric heater. The choke valve 5 is mounted upon a choke valve shaft 6 and a choke lever 7 having an elongated slot 8 is mounted upon the shaft 6.

A choke valve control system 10 according to the present invention comprises a diaphragm box 11, a pair of diaphragms 12 and 13 which are spaced apart within the box 11 to define therebetween a liquid chamber 14, and a partition wall 15 located between the diaphragms 12 and 13 bisecting the liquid chamber 14. The liquid chamber 14 may be filled with a liquid which, for example, may be oil whose viscosity is varied in accordance with variations in temperature. An orifice 16 is provided to extend through the partition wall 15 and a choke valve operating rod 17 secured to one of the diaphragms 12 is interconnected between the diaphragm 12 and the choke valve 5. A vacuum conduit 19 connects the intake manifold 2 with a diaphragm chamber

18 defined within the diaphragm box 11 by the diaphragm 13 on a side of the diaphragm 13 opposite the side of the liquid chamber 14.

Springs 20 and 21 are provided to normally bias both the diaphragms 12 and 13 in a direction toward which the control system 10 does not restrict movement of the choke valve 5.

The choke valve operating rod 17 has one end loosely fitted in sliding engagement within the elongated slot 8 in the choke lever 7. Thus, with the diaphragms 12 and 13 biased by the spring member 20 and 21 toward the right, the right hand end of the operating rod 17 will be located within the slot 8 at a portion of its operating stroke through which the rod 17 is out of driving engagement with the choke valve 5. When the rod 17 is moved to the left, as viewed in FIG. 1, the right hand end thereof will engage the end of the slot 8 thereby placing the rod 17 into driving engagement with the choke valve 5.

A check valve 22 is provided on the partition wall 15 and a valve 23 which is arranged to be opened or closed in accordance with the operating temperature conditions of the engine is provided within the vacuum conduit 19.

In the operation of the choke valve control system in accordance with the present invention, before the engine is started, the choke valve control system will be in the condition depicted in FIG. 1. That is, the diaphragms 12 and 13 will be biased to the right as shown in FIG. 1 by the springs 20 and 21, respectively, and the choke valve operating rod 17 will be out of driving engagement with the choke valve 5 by virtue of its sliding engagement with the slot 8. Furthermore, the valve 23 in the conduit 19 will remain in its closed condition.

When the engine is started, the choke valve 5 will be controlled by the bimetallic member (not shown) regardless of the behavior of the choke valve control system 10. However, when the engine has reached a specific level of warming, it is desirable to fully open the choke valve 5 in order to reduce the harmful components in the exhaust gases. For this purpose, the valve 23 is opened in response to the warmed-up condition of the engine in order to communicate the intake manifold 2 with the diaphragm chamber 18. At this point, negative pressure in the diaphragm chamber 18 actuates the diaphragms 12 and 13 in order to drive the choke valve 5 to its fully opened position against the force of the springs 20 and 21 and against the flow resistance of an orifice 16 which is defined to extend through the partition wall 15.

Under such circumstances, if the temperature of the ambient air is at a normal level, the viscosity of the liquid within the liquid chamber 14 will remain quite low so that the flow resistance of the orifice 16 is also quite small. Accordingly, the diaphragms 12 and 13 will be quickly drawn to the left, as viewed in FIG. 1, in order to fully open the choke valve 5. This enables a quick decrease of harmful components in the exhaust gas.

On the other hand, if ambient air temperature is extremely low, the viscosity of the liquid in the liquid chamber 14 will be increased in accordance with such ambient temperature and as a result the flow resistance of the orifice 16 will also be elevated. Thus, the diaphragms 12 and 13 will be drawn to the left more slowly in order thereby to effect a more gradual opening of the choke valve 5. This type of operation elongates the operating time of the choke valve and im-

proves the characteristics of engine operation at cold start.

The check valve 22 located on the partition wall 15 is arranged such that it will be in the opened condition, as depicted in FIG. 2, when no vacuum is applied in the diaphragm chamber 18, with the valve 22 being actuated to its closed condition, depicted in FIG. 3, when vacuum acts upon the diaphragm chamber 18. Thus, when vacuum in the diaphragm chamber 18 is released, the diaphragms 12 and 13 will be quickly returned to the positions thereof indicated in FIG. 1.

While a specific embodiment of the invention has been shown and described in detail to illustrate the application of the inventive principles, it will be understood that the invention may be embodied otherwise without departing from such principles.

What is claimed is:

1. A choke valve control system for an internal combustion engine which includes an intake manifold and a choke valve, said control system comprising, in combination, a diaphragm box, a pair of diaphragms located within said box and spaced apart from each other to define within said box a liquid chamber therebetween, said liquid chamber being adapted to contain therein a liquid which will undergo viscosity change in accordance with changes in temperature, a partition wall within said box bisecting said liquid chamber, orifice means defined through said partition wall, a choke valve operating rod interconnected between one of said diaphragms and said choke valve, and movable through an operating stroke between positions into and out of driving engagement with said choke valve, a diaphragm chamber defined within said box by the other of said diaphragms on a side thereof opposite said liquid chamber, vacuum conduit means connected between said intake manifold and said diaphragm chamber, and spring means biasing both said diaphragms toward a direction tending to place said operating rod out of driving engagement with said choke valve whereby introduction of vacuum in said diaphragm chamber will be communicated through said liquid chamber to drive both said diaphragms in a direction tending to bring said operating rod into driving engagement with said choke valve.

2. A system according to claim 1 including a check valve located in said partition wall and adapted to open and close in response to vacuum applied in said diaphragm chamber.

3. A system according to claim 1 including valve means located in said conduit means and adapted to open and close in response to the operating temperature of said engine.

4. A system according to claim 2 wherein said orifice means comprise a pair of orifices defined through said partition wall and wherein said check valve comprises a member adapted to be moved to open and close one of said orifices in response to vacuum applied in said diaphragm chamber.

5. A system according to claim 1 wherein said liquid contained within said liquid chamber exhibits increasing viscosity levels with decreasing temperature levels.

6. A system according to claim 1 wherein said operating rod is arranged to move said choke valve toward its open position when brought into driving engagement therewith.

7. A system according to claim 3 wherein said valve means is arranged to open and to maintain said conduit means in flow communication between said intake manifold and said diaphragm chamber when said engine operating temperature is above a predetermined level.
